UNITED STATES PATENT OFFICE.

SEBASTIAN HAAS, OF BUFFALO, NEW YORK.

WINDOW-FRAME.

Specification of Letters Patent No. 19,362, dated February 16, 1858.

To all whom it may concern:

Be it known that I, SEBASTIAN HAAS, of Buffalo, in the county of Erie, in the State of New York, have invented a new and 5 useful Improvement in Window-Frames; and I do hereby declare that the following is a full and exact description thereof, reference being had to the accompanying drawings and to the letters of reference 10 marked thereon.

The nature of my invention relates to the plan of constructing the frame and the adaptation and operation of the sash therein as hereinafter particularly set forth. The 15 drawings show the window frames in separate parts.

Figure I is a plan of the two sash as they stand together in the frame. (A) being the cap or upper casing of the frame. Fig. II 20 is a plan of the left-hand jamb with sash grooves and stops therein. Fig. III is a plan of the right-hand jamb, with sash grooves and stops therein.

f, and *f*² and *g* and *g*² are the grooves 25 which conduct the sash into and out of the frame. These grooves are cut in the jambs and guide and hold the sash. There are pins or nibs projecting from the upright stiles of the sash as represented at *O*, *O*, and 30 *O'*, *O*². These nibs are made to fit the grooves, and hold the sash in place. When it is required to put the upper sash into the jamb, the nibs *O*, *O*, in the left stile are dropped into the grooves *f*, and *g*, of the 35 left jamb and the nibs *O'*, *O*², of the right stile, pass in through the groove *f*² and *g*² into the grooves *f* and *g*, and the sash then drops down to the bottom and passes into the groove, *h*, then it is raised in the groove 40 (*h*) to its place in the upper part of the frame, and held there by a friction spring on the stile, or by spring catches (as represented at *m*, and *n*, in the bottom sash). The bottom sash is put into the frame in 45 the same manner, and passes into the grooves *h*, *h* and takes its place directly under the upper sash, so that the upper sash will in fact set on the under sash. The cross rails of the two sash are beveled, their bevels 50 nicely fitting together. A molding is put

across the rail of the upper sash, on the outside, and across the cross rail of the under sash (represented at *r*) upon the inside, these are made to fit so perfectly, as to effectually shut out the wind and rain and they present 55 the same appearance on both sides.

I, represents a stop. The nibs *l* and *m* fit snugly into the grooves *f*², and *g*², and serves to hold the sash in place. When it is required to take the sash out of the frames, 60 this stop is in the first place removed. The spring catches, *n*, *n*, are then turned back, and the lower sash raised up in the grooves (*f* and *g*) and the nibs *O'*, *O*², will pass out at the grooves *f*², and *g*², and the sash is 65 liberated from the frame. The upper sash is then dropped down to the bottom and passes up the grooves *f* and *g*, and out of the frame in the same manner.

By this arrangement of the sash and 70 grooves in the frame, the sash may be more easily and conveniently taken out of the frame for washing and cleaning and again replaced, and when in the frame they are held there perfectly secure, and at the 75 same time are easily and economically fitted to the frame, so as to shut out the inclemency of the weather.

It will be observed that the drawings represent the right jamb B, and left jamb C as 80 separated from the cap A and sill D. The cap is also represented in plan. Now if these parts are supposed to be brought together in due form the frame will be complete. The lower sash stand on the sill D. 85 K, K, moldings or stops on the frame, on the outside against which the sash rest.

Weights may be attached to the sash and the sash raised and lowered thereby as usual. The whole may be constructed by an ordinary 90 mechanic skilled in the art.

Having now fully described my invention, I claim—

The arrangement of the grooves *f*, *f*², *g*, *g*² and *h*, in the frame and the operation of 95 the sash therein, as herein described.

SEBASTIAN HAAS.
